UNITED STATES PATENT OFFICE.

WERT T. REED, OF MILWAUKEE, WISCONSIN.

BOOK-HOLDER.

1,228,136.

Specification of Letters Patent. Patented May 29, 1917.

Application filed May 13, 1914. Serial No. 838,222.

To all whom it may concern:

Be it known that I, WERT T. REED, a citizen of the United States, and resident of Milwaukee, in the county of Milwaukee and State of Wisconsin, have invented certain new and useful Improvements in Book-Holders; and I do hereby declare that the following is a full, clear, and exact description thereof.

10 My invention has for its object to provide, as a new article of manufacture, a simple, economical and efficient book-holding bracket, the same being so constructed and arranged that a book may be supported 15 at a convenient visual angle and at the same time held flatly open at the desired page without obstructing the reading matter thereon, it being understood that the bracket is also capable of being utilized as 20 a book-marker only, under which condition the support therefor is folded upon the body of the bracket.

With the above objects in view the invention consists in certain peculiarities of 25 construction and combination of parts as set forth hereinafter with reference to the accompanying drawings and subsequently claimed.

In the drawings

30 Figure 1 represents a face view of a book-holder bracket embodying the features of my invention, the same being shown with parts broken away and in section to more clearly illustrate the construction and with 35 dotted lines indicating the outline of a book fitted therein;

Fig. 2, a similar view of a modified form of my invention, and

Fig. 3, a side elevation of said modified 40 form.

Referring by characters to the drawings, 1 represents a backing strip which is preferably formed from a thin metal plate covered by suitable ornamental material. 45 The lower horizontal edge of the plate is bent upon itself to form an upwardly extending lip 2, which lip is spaced a predetermined distance from the face of the plate to form a receiving cavity for an open book. The central portion of the lip is 50 merged into an elongated extension forming a tongue 3, which tongue is adapted to engage the fold between the leaves of the book and thus hold said book in an open position without obstructing the reading matter upon the pages thereof and the semi-

circular lip at the base of the tongue is also of such dimensions as to only engage the margin of the leaves of said book. Hence it is apparent that a book of any size, after being opened at the desired pages, can be inserted between the backing and the confining mechanism comprising the lip and tongue to thus hold said book in the desired open position for perusal.

60 In order to support the book at the proper visual angle, the rear face of the backing strip 1 is provided with a leg 4 that is hingedly connected to said backing and adapted to fold thereupon. When extended, 65 as shown in Fig. 3, the supporting leg is held at the desired angle relative to the backing by a stay-strip 4'.

70 Referring to Fig. 2 of the drawings, the backing-strip 1' is provided with a top and bottom lip 2', 2'', respectively, which lips are extended outwardly from the horizontal edges of the backing plate. In this form of 75 my invention the backing-strip is of approximately the same height as the book and hence the lips will engage the marginal edges of the pages midway between their folds to thus hold said book in a desired open position. In this exemplification of 80 my invention the top lip 2' is connected to the upper horizontal edge of the backing-strip 1' by means of a spring hinge 5, whereby said lip may be swung open in order to facilitate the insertion of the book. In this form of lip it is apparent that the 85 spring hinge will serve to more effectually flatten out the book and hold it in the desired position. It is also apparent that I may, without departing from the spirit of 90 my invention, utilize rigid upper and lower lips for engagement with the book similar to the rigid lips 2 or 2'', as shown respectively in Figs. 1 and 2 of the drawings.

95 It is also within the scope of my invention to utilize a tongue similar to that shown in Fig. 1, in connection with either or both lips as shown in the modified form, it being apparent that the tongue may, in some instances, be of such resiliency as to permit expansion and contraction, whereby 100 the book is more securely held between its pages.

When it is desired to use the holder bracket as a book-marker only, the leg 4 may be closed or folded in upon the rear 110 face of the backing-strip.

It will be manifest that the book holder

is of such construction that it can readily be slid to one side of its central position when attached to a book, whereby the book can be closed while the holder will remain 5 as a marker without appreciably increasing the thickness of said book when closed. This device is particularly convenient and desirable for use in connection with bibles or prayer books that are carried back and 10 forth from places of worship, and its simplicity of construction is therefore essential.

I claim:

As a new article of manufacture, a combined book-holder and marker comprising, 15 in combination, a body plate acting as a support for the back of a book and having one end portion directed laterally and inwardly to form a leaf receiving recess, a centrally disposed tongue of restricted 20 width formed integral with said end portion and extending upwardly at a spaced

distance from the face of said plate, a lip on the other end of said body and having a spring hinged connection therewith, said spring connection tending to urge said lip 25 toward the face of said plate to more securely retain the book in the holder, and supporting means carried by the plate for holding the same in an inclined position, said supporting means being foldable to lie 30 against the body of the plate to adapt the device for use as a marker, substantially as described.

In testimony that I claim the foregoing I have hereunto set my hand at Milwaukee in 35 the county of Milwaukee and State of Wisconsin in the presence of two witnesses.

WERT T. REED.

Witnesses:

N. E. OLIPHANT,
M. E. DOWNEY.
